UNITED STATES PATENT OFFICE

163,015

TELEVISION CABINET

Samuel E. Adler, Chicago, Ill., assignor to Admiral Corporation, Chicago, Ill., a corporation of Delaware

Application December 22, 1950, Serial No. 13,536

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet of which the following is a specification, reference being had to the accompanying drawing, forming part thereof.

Fig. 1 is a front elevational view of a television cabinet showing my new design, the doors thereof being closed;

Fig. 2 is an elevational view of the left side of the cabinet;

Fig. 3 is a fragmentary view, drawn to an enlarged scale, of the lower left portion shown in Fig. 1;

Fig. 4 is a fragmentary view, drawn to an enlarged scale, of the upper left portion as shown in Fig. 1; and

Fig. 5 is a sectional view on line 5—5 of Fig. 1. The right side of the cabinet resembles the left side and the back is plain.

I claim:

The ornamental design for a television cabinet, as shown and described.

SAMUEL E. ADLER.
